A. Horney

UNITED STATES PATENT OFFICE.

PAUL J. SIMMEN, OF EDEN, NEW YORK.

TRAIN-CONTROL SYSTEM.

Application filed March 17, 1922. Serial No. 544,489.

To all whom it may concern:

Be it known that I, PAUL J. SIMMEN, a citizen of the United States, residing at Eden, in the county of Erie and State of New York, have invented certain new and useful Improvements in Train-Control Systems, of which the following is a specification.

This invention relates to train control systems and more particularly to a system wherein the electrical receiving devices employed to effect some phase of train control, for example signalling, are responsive to conditions created at a central office, thereby to enable the despatcher to prescribe traffic conditions which will conform to the requirements of safety and at the same time will involve the most effective utilization of track capacity.

The principal object of the invention is to insure the safety of such a system by making certain provision for the suitable conditioning of the appropriate electrical receiving device under conditions of danger independently of, and possibly contrary to, the action of the despatcher, thereby in any case to secure the proper regulation of the movement of the train when danger conditions maintain and so long as such conditions persist.

Stated otherwise the principal object of the invention is to promote facility of operation and the utilization of maximum track capacity while at the same time invariably to produce under conditions of danger that regulation of the movement of the train which will conform to such conditions and promote or insure safety of operation, and to render ineffective any attempted conditioning of the receiving device by the despatcher as for clear or other traffic conditions except danger.

A further object of the invention is to provide a system wherein the above purposes are served in connection with the operation of means, conditioned by the despatcher, for recording the movements of vehicles in relation to station or block divisions for which clear signals may have been effected by the despatcher.

With the above objects in view the invention consists generally in a system having train movement regulating means which is controlled automatically by a track circuit

as conditioned by the movement of a vehicle or manually by a despatcher's switch and wherein an operation of said means appropriate to conditions of danger may be effected by the despatcher's switch and under conditions of danger will be certainly and automatically effected by the track circuit as conditioned by the preceding vehicle but wherein an operation of said train movement regulating means by the despatcher's switch appropriate to clear traffic conditions or generally to traffic conditions other than danger is subject to the condition of said track circuit. Thus, assuming that the regulating means consists of signals, a danger signal can be produced either by the despatcher's switch or the track circuit but under actual danger conditions will in any case be produced automatically by the track circuit and at such time the condition of the track circuit, as produced by the preceding vehicle, will prevent a clear signal or any signal other than a danger signal being given, by an operation of the despatcher's switch; the invention also consists in the provision, in combination with the above features, of means which is conditioned by the despatcher and is subject to the controlling track circuit for recording the movements of vehicles in relation to station or block divisions for which clear signal indications may have been given by the despatcher; the invention also consists generally in novel features of structure, combination and arrangement appurtenant to a system having the distinguishing characteristics stated.

In the accompanying drawings: 90

Figure 1 is a diagram showing a system in which the features of the invention are incorporated in a form wherein the regulating means consists of cab signals.

Figure 2 is a diagram showing the cab circuits.

Figure 3 is a diagram showing a system wherein the regulating means consists of fixed signals.

Referring to Figures 1 and 2: 100

For the transmission of regulating currents I preferably use, in accordance with known practice, short third rails or ramps. Along the track 1, which may be assumed to run east and west, are a number of stations A, B, C, D, E, etc., which may be actual

- stations or other convenient dividing points between blocks, station A being assumed to be a terminal of the road or of a division thereof. The third rails are also provided
- 5 at each station and, preferably and in accordance with known practice, are connected in pairs, each pair comprising a "home" rail 3 and a "distant" rail 4. These rails may be provided for each direction of train
- 10 movement and are located on the right hand side of the track but as a matter of convenience and to simplify the illustration they are shown in the drawings only for trains west bound from station A. The car
- 15 or locomotive indicated diagrammatically by the showing of the truck T is provided with a movable shoe 5 for engagement with the third rails, the shoe 5 first engaging the distant rail and thereafter the home rail.
- 20 The cab circuits are controlled by the condition of the third rails 3 and 4 and in the embodiment selected for the purpose of illustration include signal lamps as the regulating devices. An energized condition of
- 25 said third rails produces a clear signal and a de-energized condition produces a danger signal. For the purpose of illustration it is assumed that the rails are to be energized by direct current.
- 30 The cab circuits and the signal lamps for regulating train movements are shown in Figure 2. A simple arrangement of two-lamp circuits, such as is shown in my prior Patent No. 941,541 of November 30, 1909
- 35 has been selected for the purpose of illustration. The car carries a relay CR which may be of any desired character and is used to control the operation of the signal lamps. The relay CR, as shown, includes an ordinary magnet 6 and a pivoted armature 7 which moves against a front contact 8 when the magnet is energized and against a back contact 9 when the magnet is deenergized. The magnet 6 is energized by current supplied through the third rails 3—4 or by current supplied from a suitable source, for example a battery 10, carried by the car. When the shoe 5 is engaged with an electrified third rail 3—4 current flows by the wire
- 40 11 to the magnet 6 and thence by the wires 12 and 13 to ground. When the shoe 5 is engaged with a de-energized third rail no current is supplied to the magnet 6. When the shoe 5 passes from an energized third rail,
- 45 current is supplied to the magnet by the battery 10 and the energization of the magnet is thus continued until it is interrupted, as will presently appear, by the engagement of the shoe 5 with a de-energized third rail.
- 50 When the shoe 5 passes from a de-energized third rail no current is supplied to the magnet which thus remains de-energized until such time as its energization is established by the engagement of the shoe 5 with an
- 55 energized third rail. When the magnet 6 is

energized a clear signal is displayed and when the magnet 6 is de-energized a danger signal is displayed, the clear signal being given by a green lamp 14 and the danger signal by a red lamp 15.

One pole of the battery 10 is permanently connected to the armature 7 and said battery is in a normally maintained circuit which establishes the lighting of the clear signal lamp 14. Such circuit includes the magnet 6, the armature 7, the front contact 8 and the wires 11 and 12 and is completed by a suitable switch 16 movable with the shoe 5 and normally (i. e. when said shoe is not in engagement with a third rail) engaging a contact 17 connected by a wire 18 to the front contact 8. This circuit may be traced as follows: battery 10, armature 7, front contact 8, wire 18, contact 17, switch 16, shoe 5, wire 11, magnet 6 and wires 12 and 19 to battery. The circuit thus traced is broken at the contact 17 when the shoe 5 is in engagement with a third rail.

When the magnet 6 is energized another circuit is established for the lamp 14 and which may utilize the battery 10 or other suitable source. As shown the circuit for the lamp 14 may be traced from battery 10 through armature 7, front contact 8, wire 20, lamp 14, and wires 21 and 19 to battery.

When the magnet 6 is de-energized a circuit is established for the lamp 15 and which may utilize the battery 10 or other suitable source. As shown the circuit for the lamp 15 may be traced from battery 10 through armature 7, back contact 9, wire 22, lamp 15 and wires 23 and 19 to battery.

It will be noted that the particular signal established in accordance with the condition of the third rail with which the shoe 5 is engaged is continued after the vehicle passes by the third rail and until the shoe 5 engages with a third rail having a different electrical condition. The third rail is formed, in accordance with standard practice, with inclined end portions (not shown) to facilitate the engagement of the shoe 5 and the parts are so arranged that the switch 16 will engage the contact 17 before the shoe 5 completely disengages the third rail. Consequently, in the case of an energized third rail, the energization of the magnet effected through the circuit in which said rail is included is uninterruptedly continued when the vehicle passes beyond the third rail by the local holding circuit which includes the battery 10 and the switch 16; and in this way the lighting of the lamp 14 to give a clear signal as effected by the contact of the shoe 5 with an energized third rail is continued until the shoe 5 engages a de-energized rail, at which time, the local holding circuit being broken at the contact 17, no current is supplied to the magnet 6.

When the magnet is thus de-energized by

the engagement of the shoe 5 with a de-energized third rail, the armature 7 falls against the back contact 9 and closes the circuit of the lamp 15, thus producing the 5 danger signal which is continued until the shoe 5 engages an energized rail, it being apparent that after the vehicle leaves a de-energized rail the local holding circuit of the magnet is broken at the contact 8, and 10 that the armature 7 will remain in engagement with the contact 9 until such time as current is supplied to the magnet through an energized third rail.

In the embodiment disclosed the electrical 15 condition of the third rails is subject to control, under conditions to be described, by switches at the despatcher's office and which are designated generally as 26, there being a switch for each station or block division 20 A—E, etc., of the road and the switches being connected in multiple to the corresponding blocks. These switches are indicated merely diagrammatically in the drawings and are differentiated by the same letters as the stations to which they severally 25 correspond. As shown, they include rocker shafts 27 by which they are mounted and each shaft 27 is connected by a wire 28 to the signal rails 3—4 of the corresponding 30 station, the connection being made through a track relay TR.

Any suitable arrangement may, of course, be provided for supplying current to the third rails in connection with their control 35 from a remote point, i. e. the despatcher's office. As herein shown the third rails are energized by current supplied from a common battery 29 which is connected by a line wire 30^a to a rail of the track 1 and 40 which may be utilized as the source of current for certain electrical receiving devices at the despatcher's office. The other pole of the battery 29 is connected to the stationary contacts of the switches 26, the connections including a common wire 30 and 45 wires 31 and 32 leading to the switch contacts. The central station equipment may include station relays SR for a purpose to be described and the magnets 33 of said relays 50 are shown as connected between the wires 31 and 32.

Each station or block division includes a battery or other source of current 34 and a relay TR having a magnet 35, said battery 55 and magnet being bridged across the track rails 1. The wires 28 are connected to the armatures 36 of the relays TR and the front contact 37 of each armature is connected by a wire 38 to the third rails 3—4 at the 60 entrance of the station or block division with which the relay TR is associated. The track rails of each block are, of course, suitably insulated from the track rails of adjacent blocks and the third rails 3—4 of each block 65 may be regarded as located at the end of

that block and suitably in advance of the point of entrance of the block next preceding, that is to say in advance of the point where the track rails of the block next preceding are insulated from the track rails of 70 the block with which the third rails are associated.

The relays TR are normally energized by current from the corresponding batteries 34, that is to say said relays are energized when 75 the station or block divisions with which they are associated are unoccupied; but when a station or block division is occupied the relay TR thereof is de-energized because of the short circuit through the vehicle. The 80 circuit from the battery 29 through the third rails is completed by the armature 36 as held by the energized magnet 35 of the relay TR against the front contact 37. This circuit is broken at the contact 37 when the 85 magnet 35 is de-energized and under such condition the closure of the switch 26 will be without effect. From these considerations it follows:

The despatcher can at all times de-energize the third rails at the entrance of any block in order to effect a danger signal. This is accomplished by disengaging the stationary and movable contacts of the corresponding switch 26, thus breaking the circuit of the battery 29 at the switch; the drawing shows the switch B-26 as thus opened whereby, in any case, to de-energize the third rails at the end of block A. The despatcher can energize the third rails at the entrance of a particular block so as to give a clear signal only when there is no vehicle in that block. This is accomplished by closing the switch 26 and is illustrated in the case of switch C-26, there being no vehicle in block C whereby the vehicle in block B will receive a clear signal as it passes the third rails at the end of that block. Under such conditions the circuit may be traced as follows: battery 29, wire 30, switch C-26 100 and associated elements, that is to say wire 31, magnet 33, wire 32, contacts of switch C-26, and wire 28 from switch C-26, armature 36 of relay TR of block C, front contact 37, wire 38 and third rails 3—4 of block B, 105 through the cab circuit as described, a rail or track 1 and wire 30^a to battery 29. However, if there be a vehicle in a block the operation of the despatcher's switch 26 to give a clear signal to a train at the entrance of that block will be ineffective. This is illustrated in the drawing in the case of block D. It will be noted that block D is occupied by a vehicle but that the corresponding switch D-26 has been closed by the despatcher. Since the vehicle in block D short circuits and thus de-energizes the relay TR of that block the circuit of the battery 29 will be broken at the front contact 37 of said relay and the third rails 3—4 at the end of 110

block C, that is to say at the entrance of block D, are automatically de-energized, notwithstanding the position of the switch D-26 for a clear signal. In this case the de-
 5 energization of the third rails at the end of block C has been effected automatically by the track circuit which includes the relay TR of block D and which has been automatically conditioned for a danger signal by
 10 the vehicle in block D; and the track circuit as thus conditioned by the vehicle in block D has rendered ineffective the attempt of the despatcher to give a clear signal at the entrance of said block by the closure of the
 15 switch D-26. Block E being unoccupied and the switch E-26 being closed the vehicle in block D will receive a clear signal before it reaches the entrance of block E. When the vehicle passes from block D into block
 20 E the battery 34 of block D will re-energize the corresponding relay TR and, the switch D-26 being closed, a vehicle which may have meantime entered block C will receive a clear signal for block D.

25 A train control system having the features above described can be advantageously supplemented by suitable apparatus at the despatcher's office for making a record of train movements and one form of such apparatus is herein shown diagrammatically. As shown, the recording apparatus includes a chart 39 in the form of a web and which is trained over any suitable arrangement of guiding and winding rollers. The web 39
 30 bears regularly spaced transverse or horizontal lines 40 indicative of divisions of time and longitudinal or vertical lines 41 indicative of the stations to which they severally correspond as shown in the drawings
 35 by the letters A, B, C, D and E. The shaft 42 of the winding roll of said web may be clock driven in any suitable manner but it is preferably driven by a ratchet wheel 43, in turn operated by a pawl 44 carried by the
 40 armature of an electromagnet 45. Current for the operation of the magnet 45 is supplied by a battery or other suitable source 46, the circuit being traced as follows: battery 46, wires 47 and 48, clock switch 49,
 45 wire 50, magnet 45 and wires 51 and 52 to battery. The recording means is employed for recording the movements of the vehicle in relation to station or block divisions for which clear signals have been given. According to the invention the recording devices are conditioned for operation by the despatcher, preferably in connection with the setting of the switches 26 to produce a clear signal, but their operation is subject to
 50 the conditions of the corresponding track circuits which control the clear signal indications.

The co-ordination of the operation of the recording devices and the switches 26 is effected by the station relays SR by which the
 55 operating circuits of said devices are controlled. The recording devices preferably consist of punches 53 which form recording perforations in the chart and are arranged to operate on or adjacent the lines 41. The punches 53 are operated by magnets 54 which are energized by current from the battery 46 or other suitable source. The circuit of the magnet 54 provided for a particular station or block division is completed when a vehicle has its shoe 5 in engagement with an energized third rail 3-4 at the entrance of such station or block division. The drawing shows a vehicle in block
 60 D and the diagram assumes that the shoe 5 of the vehicle is engaged with the energized third rail 4 at (i.e. suitably in advance of) the entrance of block E. In such case the relay SR for station E is energized and the circuit of the corresponding magnet 54 may be traced as follows: battery 46, wires 47 and 49, armature 55 and front contact 56 of relay SR, wire 57, magnet 54 and wires 58, 59 and 52 to battery 46. In all cases the circuits of the magnets 54 are completed by the corresponding armatures 55 in engagement with their front contacts 56 and hence for their completion it is required that the relays SR be energized. Since these relays can never be energized except as the corresponding third rails are electrified, it follows that under danger conditions when the third rails are de-energized by the track circuits no operation of a corresponding punch 53 can take place, notwithstanding that said punch may have been conditioned for operation by the despatcher's switch. For example, the diagram assumes that the third rails of station C are de-energized consequent to a vehicle occupying block D whereas the despatcher's switch D-26 is closed; in this case the dead third rails of block C prevent the completion of the circuit of the magnet 53 of the relay SR for station D, notwithstanding that the switch D-26 is closed and it follows that the engagement of the third rails of block C by the shoe 5 of a vehicle cannot produce an operation of the punch 53.

65 Referring to Figure 3: This figure shows a system embodying the invention in which the train movement regulating elements consist of fixed signals, i. e. signals such as semaphores arranged at fixed points in relation to the blocks which they control. The track 1 is divided into blocks A, B, C, D, E, etc., in the manner described. While the invention is applicable to single lines of tracks wherein the signals are arranged at opposite sides of the rails for trains bound in opposite directions, to promote convenience and simplicity of illustration I have shown the signals arranged for one direction of travel only, it being assumed that the vehicles are moving from
 70 75 80 85 90 95 100 105 110 115 120 125 130

east to west. The fixed signals as 60 are indicated in accordance with established convention as the usual semaphore arms which by their positions show whether clear or danger conditions obtain, the showing of the arms being also symbolic of their operating mechanism which may be of any suitable construction well known in the art. In the diagram the vertical position of the arms 10 represents danger and the inclined position represents clear. Thus the signals for blocks A, C, and E are assumed to be set at clear and the signals for blocks B and D at danger.

15 Each signal 60 has the usual operating circuit to which its mechanism is responsive and which is supplied by a battery 61 and is closed through an armature 62 and a front contact 63; a clear indication is given when 20 this circuit is closed and a danger indication when it is opened. The operating circuit of each signal 60 is controlled by a relay which includes the armature 62 and a magnet 64 arranged in a circuit which must be closed 25 through the despatcher's switch 26 and also through an armature 65 and a front contact 66. In the case of the block E the despatcher's switch circuit is shown as closed in order to produce a clear signal, and may be 30 traced as follows: battery 29, wire 30 (common to all the switches 26), switch E-26 and associated elements, namely wire 31, magnet 33, wire 32, contacts of switch E-26 and wire 28 leading from said switch, armature 35 65 and front contact 66 of block E, wire 67, magnet 64, wire 68 to a rail of the track 1, and wire 30 to battery 29. The armature 65 forms an element of a track relay TR which includes a magnet 35 bridged 40 across the rails of the track 1 and normally energized by current supplied by a battery 34 also bridged across said rails in the same block. It will be noted that for a clear signal to be given by the despatcher's switch 45 the relay TR must be energized in order that the armature 65 may be engaged with its front contact 66. When the circuit of the despatcher's switch is closed the magnet 64 is energized and establishes the engagement 50 of the armature 62 with the front contact 63, thereby closing the operating circuit of the signal 60 and producing an indication of clear trackway conditions.

When a vehicle is in a block the signal at 55 the entrance of said block is automatically set at danger, notwithstanding that the corresponding despatcher's switch may be set for a clear signal. The fact that a vehicle in a block produces a danger signal at the 60 entrance to such block is due to the short circuiting and resultant de-energization of the corresponding relay TR. This condition is shown in connection with block D; in which case it is assumed, for the purpose of illustration, that the despatcher's switch D-26 is

set for a clear signal. The de-energization of the relay TR of this block has caused the despatcher's switch circuit to be opened at the front contact 66 with resultant de-energization of the magnet 64 which in turn has caused the circuit of the signal 60 to be opened at the front contact 63, the signal being thereby set at danger. When the vehicle passes from block D into block E, the despatcher's switch D-26 being still in position for a clear signal, the relay TR of block D is energized, thereby through the armature 65 and contact 66 closing the circuit of the battery 29 and energizing the magnet 64 which in turn closes the operating circuit of the semaphore and produces a clear signal.

The danger signal can, of course, always be given by the despatcher who for such purpose simply opens the appropriate switch and breaks the circuit of the battery 29 at such point. The drawing shows the signal of block B at danger consequent to the opening of the circuit of the battery 29 by the switch B-26.

The recording means at the despatcher's office includes the chart 39 constructed and operated as in the previous embodiment, the perforating punches 53 and their operating magnets 54, and the station relays SR having the magnet 33 and the armatures 55. Whereas in the embodiment of Figure 1 the circuits of the magnets 54 are closed by the engagement of the armatures 55 against front contacts 56 consequent to the energization of the relays SR, in the embodiment of Figure 3 the circuits of the magnets 54 are closed by the engagement of the armatures 55 against back contacts 56^a consequent to the de-energization of the relays SR. In other words in Figure 1 the perforating punches are operated when the relays SR are energized and are rendered inoperative by the de-energization of said relays whereas in Figure 3 the operation is just the reverse, that is to say the relays SR as energized render the punches inoperative (maintaining their circuits open) and as de-energized cause their operation by permitting the armatures 55 to engage the back contacts 56^a. The opening of the circuit of the battery 29 by the presence of a vehicle in a block will, of course, de-energize the relay SR corresponding to said block, thereby causing the closing of the circuit of the magnet of the corresponding recording punch with a resultant operation of said punch.

The armature 55 will remain in position to close the circuit of the magnet 54 throughout the period in which the corresponding block is occupied by a vehicle or in which the signal for said block is set at danger and it becomes necessary to make provision for the momentary energization of the punch operating magnet 54 since the perforating

punch 53 would otherwise impede the movement of the chart 39 or produce an undesirable slit in said chart. It is preferred to cause the punch 53 to make a series of perforations at regular intervals and for this purpose I may use a clock driven interrupter such as is shown for a similar purpose in my prior Patent No. 1,257,412 of February 26, 1918 and is herein indicated at 70, this interrupter being connected between the wires 49 and 49^a. It is further to be noted that in the embodiment of Figure 3 each perforating punch is not only operated in consequence of the movement of a vehicle into the block to which the punch corresponds but is also operated whenever the danger signal for the corresponding block is given by the despatcher's switch, its operation in such case recording the fact that the switch has been set at danger for the period indicated by the extent of the punches. This is shown in the diagram of Figure 3 in the case of the switch B-26 which has been set for danger with resultant operation of the corresponding perforating punch.

The system herein described gives the despatcher the greatest facility in regulating train movements and utilizing maximum track capacity while at the same time insuring entire safety of operation by preventing the despatcher through inadvertence or mistake from giving a false clear signal. These results in the aggregate are essentially secured by the combination of operating circuits controlled from a remote point by the despatcher and local track circuits to which the despatcher's control of the operating circuits is subject.

It will, of course, be understood that the diagrams herein shown are, while complete in their disclosure of the invention, merely schematic.

Having fully described my invention, I claim:

1. In a system of train control, in combination, a line of track, means having different phases of operation for regulating the movement of trains, electrical means operative according to its condition for producing one or another operation of said regulating means, and means for characteristically conditioning said electrical means including a controlling element manually operated from a fixed remote point and having selected maintained positions to effect and maintain such characteristic conditioning, and a second controlling element automatically operative in accordance with the occupied or unoccupied condition of said line of track and to which the conditioning operation of the manually operated element is subject, thereby to prevent a regulation for clear trackway conditions falsely responsive to a corresponding operation of said manually operated element.

2. In a system of train control, in combination, a line of track, means having different phases of operation for regulating the movement of trains, electrical means operative according to its condition for producing one or another operation of said regulating means and means for characteristically conditioning said electrical means including a controlling element manually operated from a fixed remote point and having selected maintained positions to effect and maintain such characteristic conditioning, an electrically operated controlling element to which the conditioning operation of the manually operated element is subject, and a circuit connected to the line of track and in which the electrically operated element is included, the electrically operated element being automatically responsive in its particular operations to the occupied or unoccupied condition of said line of track, thereby to prevent a regulation for clear trackway conditions falsely responsive to a corresponding operation of said manually operated element.

3. In a system of train control, in combination, a line of track, signal means adapted for clear and danger indications, electrical means operative according to its condition for producing one or another indication of said signal means, and means for characteristically conditioning said electrical means including a controlling element manually operated from a fixed remote point and having selected maintained positions to effect and maintain such characteristic conditioning, and a second controlling element automatically operative in accordance with the occupied or unoccupied condition of said line of track and to which the conditioning operation of the manually operated element is subject, thereby to prevent a regulation for clear trackway conditions falsely responsive to a corresponding operation of said manually operated element.

4. In a system of train control, in combination, a line of track, signal means adapted for clear and danger indications, electrical means operative according to its condition for producing one or another indication of said signal means, and means for characteristically conditioning said electrical means including a controlling element manually operated from a fixed remote point and having selected maintained positions to effect and maintain such characteristic conditioning, an electrically operated controlling element to which the conditioning operation of the manually operated element is subject and a circuit connected to the line of track and in which the electrically operated element is included, the electrically operated element being automatically responsive in its particular operations to the occupied or unoccupied condition of said line of track, thereby to prevent a regulation for clear

trackway conditions falsely responsive to a corresponding operation of said manually operated element.

5. In a system of train control, in combination, a line of track, a vehicle thereon, signal means carried by the vehicle and adapted for clear and danger indications, electrical means also carried by the vehicle and operative according to its condition for 10 producing one or another indication of said signal means, and means operative in relation to a fixed division of the line of track for conditioning said electrical means and including a controlling element manually operated from a fixed remote point and a second controlling element automatically operative in accordance with the occupied or unoccupied condition of said fixed division of said line of track and to which the conditioning 15 operation of the manually operated element is subject, thereby to prevent a regulation for clear trackway conditions falsely responsive to a corresponding operation of said manually operated element.
- 20 6. In a system of train control, in combination, a line of track, a vehicle thereon, signal means carried by the vehicle and adapted for clear and danger indications, electrical means also carried by the vehicle 25 and operative according to its condition for producing one or another indication of said signal means, and means operative in relation to a fixed division of the line of track for conditioning said electrical means and 30 including a controlling element manually operated from a fixed remote point, and an electrically operated controlling element to which the conditioning operation of the manually operated element is subject and 35 a circuit connected to the fixed division of the line of track and in which the electrically operated element is included, the electrically operated element being automatically responsive in its particular operations 40 to the occupied or unoccupied condition of said fixed division of the said line of track, thereby to prevent a regulation for clear trackway conditions falsely responsive to a corresponding operation of said manually 45 operated element.
- 50 7. In a system of train control, in combination, train movement regulating means, electrical means of characteristically variable condition to which said regulating 55 means is characteristically responsive in operation, an electrical circuit by which said electrical means is characteristically conditioned, manually operated means for characteristically conditioning said circuit from 60 a fixed remote point, a line of track and means automatically operative characteristically in accordance with the occupied or unoccupied condition of said line of track for characteristically conditioning said circuit, the conditioning of the circuit by said 65

manually operated means to produce a certain operation of said regulating means being subject to the operation of said automatically operative means, thereby to prevent a regulation for clear trackway conditions 70 falsely responsive to a corresponding operation of said manually operated means.

8. In a system of train control, in combination, train movement regulating means, electrical means of characteristically variable condition to which said regulating means is characteristically responsive in operation, an electrical circuit by which said electrical means is characteristically conditioned, manually operated means for characteristically conditioning said circuit from a fixed remote point, a line of track, an electrical circuit connected to said line of track, and having means therein automatically operative characteristically in accordance with the occupied or unoccupied condition of said line of track for characteristically conditioning said first named circuit, the conditioning of the first named circuit by said manually 85 operated means to produce a certain operation of said regulating means being subject to the operation of said automatically operative means, thereby to prevent a regulation for clear trackway conditions 90 falsely responsive to a corresponding operation of said manually operated means.

9. In a system of train control, in combination, train movement regulating means, electrical means of characteristically variable condition to which said regulating means is characteristically responsive in operation, an electrical circuit by which said electrical means is characteristically conditioned, manually operated means for characteristically conditioning said circuit from a fixed remote point, a line of track, an electrical circuit connected to said line of track and having a relay therein responsive in operation to the occupied or unoccupied condition of said line of track for characteristically conditioning said first named circuit, the conditioning of the first named circuit by said manually operated means to produce a certain operation of said regulating means being subject to the operation of said relay, thereby to prevent a regulation for clear trackway conditions 100 falsely responsive to a corresponding operation of said manually operated means.

10. In a system of train control, in combination, a line of track, means having different phases of operation for regulating the movement of trains, electrical means operative according to its condition for producing one or another operation of said regulating means, means for conditioning said electrical means including a controlling element manually operated from a fixed remote point and a second controlling element 105 automatically operative in accordance with 110 115 120 125 130

- the occupied or unoccupied condition of said line of track and to which the conditioning operation of the manually operated element is subject, electrically operated means for 5 recording train movements and means also conditioned by said manually operated element and subject to said second controlling element for producing an operation of said recording means.
- 10 11. In a system of train control, in combination, a line of track, signal means adapted for clear and danger indications, electrical means operative according to its condition for producing one or another indication 75 of said signal means, means for conditioning said electrical means including a controlling element manually operated from a fixed remote point and a second controlling element automatically operative in accordance with 80 the occupied or unoccupied condition of said line of track and to which the conditioning operation of the manually operated element is subject, electrically operated means for recording train movements and means also 85 conditioned by said manually operated element and subject to said second controlling element for producing an operation of said recording means.
12. In a railway train control system, in 90 combination, a trackway divided into blocks, a train control rail for each block arranged on one side of the trackway, a source of current, manually operated elements, one for each block, located at a common remote 95 point for connecting or disconnecting one terminal of the source with the track control rail, and means controlled by the presence of a train upon a block to which the effective operation of the correspondingly 100 manually operated means is subject, thereby to prevent a regulation for clear trackway conditions falsely responsive to a corresponding operation of any of said manually operated elements.
13. In a railway train control system, in combination, a trackway divided into blocks, a source of current, train control means for each block and to which current may be supplied from said source, switches, one for 105 each train control means, located at a common remote point and in circuit with said source, each switch being manually operable to connect or disconnect one terminal of the source to the corresponding train control 110 means, a trackway battery for each block, and a relay for, and energized by, each battery by which the supply of current to each train control means through the corresponding remote switch is controlled, thereby to 115 prevent a regulation for clear trackway conditions falsely responsive to a corresponding operation of any of said switches.
14. In a system of train control, in combination, a line of track, means having different phases of operation for regulating 120 the movements of trains, electrical means operative according to its condition for producing one or another operation of said regulating means, means for conditioning said electrical means including a controlling 125 element manually operated from a fixed remote point and a second controlling element automatically operative in accordance with the occupied or unoccupied condition 130 of said line of track and to which the conditioning operation of the manually operated element is subject, electrical operating means for indicating train movements, and means also conditioned by said manually operated element and subject to said controlling elements for producing an operation of said indicating means.
15. In a system of train control, in combination, a line of track, signal means adapted for clear and danger indications, electrical means operative according to its condition for producing one or another indication of said signal means, means for conditioning said electrical means including a controlling element manually operated from a fixed remote point; and a second controlling element automatically operative in accordance with the occupied or unoccupied condition of said line of traffic and to which the conditioning operation of the manually operated element is subject, electrically operated means for indicating train movements, and means also conditioned by said manually operated element and subject to said controlling element for producing an operation of said indicating means.
16. In a system of train control, in combination, a track-way divided into blocks, train control means for each block, a common source of current for the train control means, a manually operated controlling element for each train control means, the manually operated elements being located at a fixed remote point, a track battery and a track relay for each block, and a control circuit for each train control means taken from the common source through the corresponding manually operated element and the corresponding relay, and having a terminal ground, the other side of the common source being also grounded, said circuit thereby being capable of being broken in two places, manually at said controlling element and automatically at said track relay, thereby to prevent a regulation for clear trackway conditions falsely responsive to a corresponding operation of said manually operated element.
17. In a system of train control, in combination, a track-way divided into blocks, train control means for each block, a common source of current for the train control means, a manually operated controlling element for each train control means, the manually operated elements being located at

a fixed remote point, a track battery and a track relay for each block, a control circuit for each train control means taken from the common source through the corresponding 5 manually operated element and the corresponding relay and having a terminal ground, the other side of the common source being also grounded, said circuit thereby being capable of being broken in two 10 places, manually at said controlling element and automatically at said track relay, thereby to prevent a regulation for clear trackway conditions falsely responsive to a corresponding operation of said manually operated element, an electrically operated 15 indicating device for each block, and a circuit for said indicating device taken from said common source through said manually operated controlling element whereby said indicating device is responsive in operation 20 to a particular condition of said train control means.

In testimony whereof I affix my signature.
PAUL J. SIMMEN.
